UNITED STATES PATENT OFFICE.

RICHARD F. BARKER, OF BELLOW'S FALLS, VERMONT.

PROCESS AND APPARATUS FOR DESICCATING LIQUIDS.

1,362,590.

Specification of Letters Patent. Patented Dec. 21, 1920.

Application filed June 23, 1919. Serial No. 306,137.

To all whom it may concern:

Be it known that I, RICHARD F. BARKER, a citizen of the United States, residing at Bellows Falls, in the county of Windham 5 and State of Vermont, have invented or discovered certain new and useful Improvements in Processes and Apparatus for Desiccating Liquids, of which the following is a specification, reference being had therein 10 to the accompanying drawing.

My invention relates to the separation of moisture from the constituent solids of liquids or semi-liquids and recovering such solids in a substantially dry or desiccated 15 form, and it has reference more particularly to the desiccation of milk, skimmed or whole, and of cream. The object of the invention is the desiccation of animal, vegetable, or other substances, normally in a 20 liquid or semi-liquid form, the solids of which it is desirable to reduce to dryness quickly, and without substantial change to their chemical or physical structure.

Previous desiccating processes for liquids 25 containing proteins, sugar, or like substances which are extremely sensitive to heat, have been mainly of two classes; one, atomizing the liquid in a hot current of air, and the other, the drawing out of the 30 liquid in a film upon a revolving surface and the subjecting of this film to heat from the surface, with or without the additional drying effect of a hot-air current over the film. These processes, though successful, are slow 35 in operation; the first requires vast quantities of heated air to effect complete desiccation, and the second is slow because the film drawn upon the revolving surface must be of excessive thinness in order to dry before 40 it is changed chemically by the heat to which it is subjected.

I have discovered that if the liquid to be desiccated, previous to being deposited in finely divided particles upon a heated surface, 45 is preheated and partially evaporated by a hot current of air while in such a finely divided state, the desiccation is extremely quick and efficient. The desiccation is further accelerated, if the particles on the 50 heated surface, before they are dried, are superimposed by other partially evaporated finely divided particles heated in a hot-air current and the whole dried finally on the hot surface while subjected to a hot-air current. My process obviates the use of large 55 quantities of hot air, and it does not re-

quire a great deal of time to evaporate a large quantity of liquid.

The liquid to be desiccated is finely divided by any convenient method, such as 60 a spray nozzle. The finely divided particles are then conveyed in a current of drying gas, preferably air, and before the evaporation of all the moisture which they contain, they are deposited on a hot surface 65 which is preferably movable. The deposited particles on the surface are subjected to the action of hot air or other drying gas. While the particles when first attached to the hot surface contain considerable moisture, other partially dried particles are superimposed thereupon, these latter particles having also been partially evaporated before they reach the particles first imposed upon the hot surface. The superimposed 70 particles are subjected to the action of a drying gas and the evaporated material is preferably removed previous to complete desiccation to avoid scorching, and this process may be repeated a predetermined 75 number of times, depending on the material to be treated and the temperature of both the drying surface and the drying gas used. In the last application of the partially dried particles, they, together with the particles 80 previously deposited on the hot surface, are evaporated to a substantial dryness, or to a solid condition, by the heat of the surface to which they cling, and by the current of dry gas passing adjacent to this surface. 85 After being so dried, they are removed from said surface by any suitable means, in the form of a thin desiccated crust or film which readily crumbles to powder. 90

In the accompanying drawing Figure 1 is 95 a sectional elevation of an apparatus by which my invention can be carried into effect, and Fig. 2 is a cross section of the same on line 2—2, Fig. 1. Fig. 3 is an end elevation of the same, partly in section, on 100 line 3—3, Fig. 1.

Referring to the drawing, 12 denotes a drying chamber into which hot air is forced through pipes 13 and 14. Mounted for vertical rotation in the chamber 12 is a hollow 105 disk-like drum 15 mounted on a horizontal axis consisting of hollow pipes 16 supported by suitable bearings, as 17, the said hollow drum being heated internally, preferably by steam conveyed to and from the chamber 110 of said drum through the said pipes 16. Communicating with the chamber of the

drum 15 are hoods 18 affording drying chambers preferably of conical form, as shown, and with which drying chambers the hot air pipes 13 communicate. The liquid to be evaporated is introduced into the drying chambers through suitable pipes as 19, terminating in nozzles 20, and the liquid as it emerges from said nozzles is preferably divided into fine particles or spray by means of air, which may be heated, introduced into the drying chambers through pipes 21 terminating in nozzles arranged closely adjacent to the ends of the nozzles 20.

15 The heated drum 15 is slowly rotated in the direction indicated by the arrow in Fig. 2 in the chamber 12, and the liquid being treated is sprayed into the drying chambers afforded by the hoods 18 and is partially evaporated to a viscous condition in said chambers, and is carried by the hot air currents in this partially evaporated and viscous condition onto the heated surfaces of the drum 15, so that it will be dried on 20 said drum in the form of a thin crust and will be removed therefrom by a stationary scraper or doctor, as 22, and when thus removed will be received in a suitable receptacle or trough 23 and will be carried outward in said trough by a helical conveyer, as 24, and discharged at an outlet 25. These scrapers, troughs and conveyers will of course be duplicated at each side of the drum 15, as will be understood.

30 35 In order to make a successive deposit of the particles to be evaporated on the surface of the heated rotating drum 15 a plurality of drying chambers afforded by the hoods 18 and into which chambers the liquid will be sprayed, 40 may be employed in connection with each surface or face of the drum. These drying chambers are arranged one behind the other in the direction of rotation indicated by the arrow in Fig. 2, of the drum 15, as will be 45 understood from Fig. 2. A conventional representation of these drying chambers is indicated by the dotted lines in Fig. 2, and these chambers may be arranged either so as to overlap each other, as indicated by the 50 dotted lines referred to, in which case the chambers will partly communicate with each other as will be understood, or they may be so arranged as to be entirely separate. It will be understood that there will be a liquid 55 conveying pipe or nozzle and an air pipe or nozzle provided for each one of these drying chambers, although, for simplicity of illustration, these atomizing pipes and nozzles for the successive chambers are not duplicated in the drawing.

60 From the foregoing it will be understood that in the operation of the apparatus shown, and in carrying the improved process into effect, the liquid or semi-liquid substance to be desiccated will be sprayed into

the drying chambers 18 where it will be heated and partly evaporated and will be forced through said chambers by the air currents entering through the pipes 13 and 21 onto the rotating heating drum 15 by 70 which the complete desiccation of the material, into solid form, in a film or crust, will be effected; and the material thus desiccated may be removed from the surfaces of the drum by scrapers or doctors, as 22, and may 75 be carried outward from the chamber 12 by conveyers, as 24. The conveyers 24 work in troughs 23 having discharging spouts 25.

The drying chamber 12 is provided with an exit pipe 26 through which the hot air, 80 more or less moisture laden, can escape from said chamber.

I find that the temperature to which it is necessary to heat the drum 15, as well as that of the gas or hot air also used for preheating and partially evaporating the particles may be varied to a considerable extent and an excellent desiccated product obtained even from delicate albuminoid substances, provided the rate of revolution of the disk 90 is increased proportionately to the increase of temperature; a very short exposure to the temperature considerably in excess of the coagulating point of albumen affecting the product no more than a longer exposure 95 at a lower temperature. I find it is preferable, however, in producing a soluble milk product, to heat the drum to a temperature of 150° F., or somewhat higher, and to limit the initial temperature of the drying 100 gas or hot air, entering through pipes 13, to about 212° F. In the treatment of milk for producing a soluble dry product it is not necessary, however, that the temperature of the air entering the spraying pipes 105 21 should be at a relatively low temperature, as much of the heat is immediately absorbed in the spraying process so that the air under pressure entering through the said pipes 21 may be considerably more than 212° F.

110 But in producing a milk powder which is not wholly soluble, owing to coagulation of the albumen but which is readily saleable for bakers' use, etc., and which may be manufactured more cheaply and quickly 115 than the soluble product, much higher temperatures than those above referred to may be employed. In such case the rotating drum 15 may be heated to a temperature of 300° F., or over and a much smaller volume 120 of highly heated air, approximately of the temperature of the drum, may be employed; the drying being done largely by the drying drum; while in producing a completely soluble product it is done largely by the heated 125 air. From this it will be understood that in the use of my improved apparatus, and in practising my improved process, the range of temperatures employed may be very wide.

One advantage of my improved process in which the material to be dried is first partially evaporated before being applied to a moving heated surface, consists in the 5 fact that the partially evaporated particles in being applied to the heated surface form a rough or irregular surface which affords a greater evaporating quality than a smooth film would; so that the drying process, comprising the use of heated air, proceeds more rapidly than it would if the heated air were brought into contact with a smooth film on the heated drying surface of the drum 15.

In the case of liquids having a moisture content of 80% or more, it may be advantageous, though not necessary, to condense the liquid by any suitable process, so that the total solids shall exceed 20 per cent., before desiccating the liquid by my process, 20 as this enables me to increase the rate of desiccation perceptibly. This, in the case of highly organized albuminoid bodies, has the additional advantage of allowing a greater heat without injuriously affecting the product, as a concentrated liquid, such, for instance, as milk, will stand a much higher heat for a short period without affecting the solubility of the final product, than were it unconcentrated.

30 The invention is not to be understood as being limited to the use of an apparatus such as is herein shown and described, or to the particular steps of the process hereinbefore set forth, as considerable variations from the described apparatus and process may be made within the scope of the appended claims or the scope of mechanical skill, without departing from the essence of the invention.

40 Having thus described my invention or discovery, I claim and desire to secure by Letters Patent:

1. The process of desiccating liquids consisting in atomizing and partially evaporating the liquid in a drying atmosphere, collecting the atomized and partly dried material, while in a viscous condition, upon a moving heated surface, further drying said material on said heated surface to obtain a 50 solid residue, and removing the said residue from the said surface.

2. The process of desiccating liquids which consists in atomizing the liquid in a drying atmosphere, by a hot current of air, carrying the atomized and partially evaporated viscous material onto a moving heated surface, by said hot current of air, further drying the material on said heated surface to obtain a solid residue, and removing the said residue from said surface.

60 3. The process of desiccating liquids which consists in atomizing and partially evaporating the liquid in a drying atmosphere

by a hot air current in a drying chamber, 65 depositing the partially evaporated viscous particles on a moving heated surface in such a manner as to produce an irregular or rough film by the successive accumulation of said particles on said surface, further drying the material on said surface to obtain a solid residue, and then removing said residue from said surface.

4. The process of desiccating liquid or semi-liquid material which consists in simultaneously spraying such material of a like 75 degree of concentration into and through a plurality of successively arranged chambers each of which has a drying atmosphere afforded by hot air currents forced therethrough, and thus heating and partially 80 evaporating the material in said chambers, successively depositing the partially evaporated material on a moving heated surface thereby forming successive layers of said material on said surface, further drying the 85 material on said surface to reduce the same to solid form, and then removing the desiccated material from said surface.

5. An improved apparatus for desiccating liquid or semi-liquid substances, consisting 90 of the combination with a hollow rotating disk or drum and means for heating the same internally, of a drying chamber inclosing said disk or drum, hot air pipes communicating with said chamber, hoods 95 arranged on opposite sides of said disk or drum and communicating with said chamber and with the chambers of which hoods said hot air pipes communicate, means for spraying the liquid or semi-liquid substance 100 to be evaporated into the chambers of said hoods and onto the opposite surfaces of said disk or drum, and means for removing the desiccated material from said disk or drum.

6. An improved apparatus for desiccating liquid or semi-liquid substances, consisting 105 of the combination with a hollow rotating disk or drum and means for heating the same internally, of a drying chamber inclosing said disk or drum, hot air pipes 110 communicating with said chamber, hoods arranged on opposite sides of said disk or drum and communicating with said chamber, and with the chambers of which hoods said hot air pipes communicate, means for 115 spraying the liquid or semi-liquid substance to be evaporated into the chambers of said hoods and onto the opposite surfaces of said disk or drum, and means for removing the desiccated material from said disk or drum, 120 a plurality or succession of said hoods being provided for each face of said disk or drum.

In testimony whereof I affix my signature.

RICHARD F. BARKER.
